MICHAEL C. SMOTZER, OF COSHOCOTON, OHIO, AND JOHN A. BYERS, OF CHICAGO, ILLINOIS, ASSIGNEES TO JAMES B. CLOW & SONS, OF CHICAGO, ILLINOIS, A CORPORATION OF ILLINOIS.

CENTRIFUGAL CASTING MACHINE AND METHOD OF CASTING.

Application filed September 18, 1926. Serial No. 134,971.

This invention relates to the art of casting iron or other pipe centrifugally, although within its scope it is equally applicable to casting any cylindrical metal object. The invention more particularly pertains to a method of and means for equalizing the flow of molten metal from the spouts or pouring lips of a distributor of the character generally used in centrifugal casting, as well as to a method of and means for preventing the molten metal from cooling and solidifying in portions of the distributor, or minimizing the effects thereof.

In the ordinary process of centrifugally casting cylindrical bodies such as iron pipe, a horizontal rotating mold is utilized. This requires a long distributor or ladle disposed axially of and within the mold, in order that the molten metal may be poured therefrom into all parts of the mold substantially simultaneously, while the mold is rotated. A distributor of the character referred to is illustrated in Patent 1,485,592, dated March 4, 1924.

In using distributors of the character to which reference has been made, molten metal to the requisite quantity to make the object to be cast is poured into one end of the distributor, which is left projecting from the mold for the purpose. As this will be clearly apparent by reference to the patent mentioned supra, no further description of it herein is deemed necessary. From the receiving end of the distributor the metal flows toward the opposite end until it has found its level throughout, or until it has been poured into the mold, or has solidified. As the tongue of the wave of metal advances along the floor or lining of the distributor, those portions of the metal stream coming in contact with the cold floor, wall or lining chill and tend to solidify. This chill occurs even though the distributor has been highly preheated, and as the heat is drawn from the metal most closely adjacent the lining of the distributor, the temperature of the molten metal is gradually reduced throughout.

The cooled metal while still fluid, becomes more and more sluggish in its flow as the temperature is further reduced by progress

along the comparatively cold lining until the temperature is so much reduced that it solidifies as a crust or skull on the refractory lining of the distributor. In other words, the contact of the molten metal with the distributor progressively draws or reduces the temperature of the molten stream as it travels along the distributor to its most remote destination. The consequence of this is self-evident. As the temperature of the metal is reduced the stream becomes more sluggish the further it travels, and therefore does not flow evenly to all portions of the mold and a comparatively large quantity of the metal which is needed to form the object to be cast becomes solidified and hardened to the refractory lining of the distributor. Both these facts prevent the metal from being evenly distributed when the metal is dumped or poured from the distributor into the mold, and a body of irregular and uneven thickness of wall results.

One of the primary purposes or objects of the invention therefore resides in the provision of the method of distributing the metal in and throughout the distributor, so that no one portion of the molten metal will travel the full length or a material part of the length of the distributor to heat the floor or lining thereof and become cooled thereby. Our process accordingly includes the retention of the initial metal that has been poured into the distributor and has flowed over a predetermined small portion of the distributor lining, within such portion, and the utilization of molten metal of high temperature for filling and heating a succeeding portion of the distributor, and so on. In other words, that metal which has been cooled by contact with the distributor lining is prevented from flowing or being carried to more remote portions of the distributor and thereby losing a vital portion of its heat, which loss might seriously affect the final product.

Another important object of the invention is to provide a distributor of the character mentioned of such construction as will properly carry out the process.

Further objects include various features of distributor construction and arrangement

which will be or should become apparent after reading the following description and claims in connection with the drawing, in which

5 Fig. 1 is a side elevational view of a preferred type of distributor for carrying out the invention.

Fig. 2 is a top plan view of the same.

10 Fig. 3 is a central, longitudinal, sectional view taken on the center line of Fig. 2, and

Fig. 4 is an enlarged transverse sectional view of the distributor taken on the line 4—4 of Fig. 2.

15 The distributor is of the general shape and arrangement of the distributor illustrated and described in the patent to which reference has been made above, comprising a semi-cylindrical shell 2 of cast iron or other 20 suitable metal terminating in a solid portion 3 at one end, and in a hollow portion 4 at the other. The end 4 is closed by a solid cap 5, preferably integral therewith, and is provided with an opening 6 into which the 25 metal is poured from a ladle or the like. The hollow interior of the end 4 communicates at 7 with the trough formed by the semi-cylindrical shell 2, which is lined from end to end with suitable refractory material 8, such as fire brick or the like.

Along one longitudinal edge of the shell 2 a cast iron strip or pouring lip member 9 having a series of projections 11 forming pouring spouts 12 between them, is secured, 35 as by means of screws 13 which pass through the shell 2 into the base portion of the strip 9. While we prefer to form the pouring lips or spouts 12 in a single strip or casting 9 as shown, it will be obvious that the spouts 40 may be formed individually or in blocks of any suitable number and attached to the shell 2 in the same or any suitable way. However the strip member or members 9 may be formed, we prefer that the bottom 45 edges of each of them shall be bevelled off as shown at 14 in Fig. 4, in order that they may serve to aid in retaining the refractory lining 8 within the shell 2. Along the opposite edge or rim of the shell and longitudinally thereof, a lining retaining strip 50 15, preferably made of steel, is secured by screws 16 or other suitable securing means in a manner similar to the manner of securing the cast iron strip or members 9 to the 55 opposite side. The bottom edge of the steel strip 15 is also bevelled off as at 17 to aid in securing the refractory lining within the shell.

In order to carry out our primary objects, 60 we insert baffles 18 at suitable intervals transversely of the shell. These baffles are constructed of refractory material preferably reinforced as at 19 with nails or any other reinforcing means, and rise from the 65 bottom of the refractory lining 8 to a height

approximately one-half the depth of the metal in the distributor, that is one-half the depth of the metal necessarily received into the distributor for forming the article desired. While these baffles may be located 70 at shorter intervals along the distributor, we have found that for casting the average length of cast iron pipe, two baffles each placed approximately one-third of the distance of the distributor shell will serve the 75 purpose very well.

When the metal is poured into the distributor through the opening 6, it first fills the compartment or portion of the distributor between the first baffle 18 and the opening 7, so that approximately one-sixth of the total charge of molten metal is received therein before any metal flows into the succeeding compartment or portion of the distributor. Likewise, the succeeding compartment receives approximately one-sixth of the total charge before its succeeding compartment or portion receives any of the molten metal, and so on until all three of the compartments or portions of the distributor are 80 filled. The operator or operators, of course, continue pouring molten metal into the opening 6 until the requisite charge has been received in the distributor. Retarding the flow of metal from one compartment or portion of the distributor to another, or in other words accumulating a predetermined portion of the charge at one place in the distributor before any metal flows to a second portion or compartment apparently equalizes the 85 temperature of the metal in each compartment, so that that metal which serves to heat the first compartment and becomes chilled thereby is reheated by the flowing metal following it and does not continue on along the distributor and become solidified at some remote portion thereof. As a consequence, 90 each compartment receives substantially the same amount of molten metal at substantially the same temperature as the metal contained within other portions or compartments, and when the distributor is tipped to pour the metal through the spouts 12, substantially the same amount of metal 95 flows out through each of the spouts, regardless of its position along the length of the shell, into the mold, and a uniform and 100 regularly walled casting results.

We have illustrated and described a preferred form of our process for obtaining a 105 uniform or regular walled casting, and have illustrated one form or embodiment of apparatus for carrying it out, but it will be 110 obvious that the method may be varied considerably and that other arrangements and 115 constructions of apparatus may be utilized to accomplish the same. We do not wish therefore to be limited by what has been 120 shown and described as a preferred embodiment of our invention, since many modifica- 125

tions fall within the spirit and purview of our invention, and scope of the appended claims.

We claim:

- 5 1. A method of casting cylindrical bodies centrifugally comprising accumulating molten metal in one portion of a distributor adapted to be disposed substantially horizontally within a mold form, until a predetermined quantity has been accumulated therein, thereafter accumulating molten metal in a successive portion of the distributor until a predetermined quantity has been received therein, and thereafter flowing the metal accumulated in the said portions from the distributor into the mold.
- 10 2. A distributor of the character described comprising, a trough adapted to extend longitudinally of and within a mold for centrifugal casting, and a series of baffles disposed transversely of the length thereof.
- 15 3. A distributor of the character described comprising, a trough having an imperforate bottom adapted to extend longitudinally of a mold, and means for retarding spread of molten metal from one portion of the trough to another until a predetermined quantity of metal has been received in the first said portion.
- 20 4. A distributor of the character described comprising, a trough adapted to be disposed horizontally over the bottom and longitudinally of a mold, said trough being adapted to retain for a desired period molten metal received therein, and means disposed at intervals along the interior of the trough for restraining the flow of molten metal from one portion of the trough to another portion until a predetermined quantity of metal has been received and retained in the first said portion.
- 25 5. A distributor of the character described comprising, a semi-cylindrical trough adapted to extend longitudinally of a mold, and transverse barriers against metal flow from one portion to another of the distributor rising from the floor of the distributor at spaced intervals therealong, said barriers being constructed and arranged to make the metal flow from one portion to another in succession only, and pouring spouts along one longitudinal edge of said trough.
- 30 6. A distributor of the character described comprising, a trough adapted to extend longitudinally of a mold, a series of baffles disposed transversely of the length thereof, and pouring spouts along one longitudinal edge of said trough, said trough having a substantially imperforate bottom.
- 35 7. A distributor of the character described comprising, a trough adapted to extend longitudinally of a mold, said trough being adapted to retain for a desired period molten metal received therein, and means for retarding spread of molten metal from one portion of the trough to another until a predetermined quantity of metal has been received and retained in the first said portion, and pouring spouts along one longitudinal edge of said trough.
- 40 8. A distributor of the character described comprising, a semi-cylindrical trough adapted to extend longitudinally of a mold, transverse barriers against metal flow from one portion to another of the distributor rising from the floor of the distributor at spaced intervals therealong, said barriers being constructed and arranged to make the metal flow from one portion to another in succession only, and pouring spouts along one longitudinal edge of said trough.
- 45 9. A distributor of the character described comprising, a semi-cylindrical trough adapted to extend longitudinally of a mold, transverse barriers against metal flow from one portion to another of the distributor rising from the floor of the distributor at spaced intervals therealong, said barriers being constructed and arranged to make the metal flow from one portion to another in succession only, and pouring spouts along one longitudinal edge of said trough.
- 50 10. A distributor of the character described comprising, a longitudinal trough adapted to receive molten metal at one end, and means for interrupting the free flow of metal from the receiving end toward the opposite end of the trough and for causing the metal to accumulate to a predetermined depth in one portion of the trough before any metal is received in an adjacent but more remote portion.
- 55 11. A method of filling a distributing trough for casting in a centrifugal casting mold comprising pouring molten metal into the trough and restricting the free spread of the molten metal from place to place along the length of the trough until a substantial quantity of molten metal has accumulated at one place.

In witness of the foregoing we affix our signatures.

comprising, a trough adapted to extend longitudinally of a mold, said trough being adapted to retain for a desired period molten metal received therein, means for retarding spread of molten metal from one portion of the trough to another until a predetermined quantity of metal has been received and retained in the first said portion, and pouring spouts along one longitudinal edge of said trough.

8. A distributor of the character described comprising, a trough adapted to be disposed horizontally over and longitudinally of a mold, said trough being adapted to retain for a desired period molten metal received therein, means disposed at intervals along the interior of the trough for restraining the flow of molten metal from one portion of the trough to another portion until a predetermined quantity of metal has been received and retained in the first said portion, and pouring spouts along one longitudinal edge of said trough.

9. A distributor of the character described comprising, a semi-cylindrical trough adapted to extend longitudinally of a mold, transverse barriers against metal flow from one portion to another of the distributor rising from the floor of the distributor at spaced intervals therealong, said barriers being constructed and arranged to make the metal flow from one portion to another in succession only, and pouring spouts along one longitudinal edge of said trough.

10. A distributor of the character described comprising, a longitudinal trough adapted to receive molten metal at one end, and means for interrupting the free flow of metal from the receiving end toward the opposite end of the trough and for causing the metal to accumulate to a predetermined depth in one portion of the trough before any metal is received in an adjacent but more remote portion.

11. A method of filling a distributing trough for casting in a centrifugal casting mold comprising pouring molten metal into the trough and restricting the free spread of the molten metal from place to place along the length of the trough until a substantial quantity of molten metal has accumulated at one place.
